CLAIM

The ornamental design for a climbable integral block formation, as shown and described.

DESCRIPTION

FIG. 1 is a top-front-right side perspective view of a climbable integral block formation, showing the design; FIG. 2 is a bottom-front-right side perspective view of the climbable integral block formation;

FIG. 3 is a top view of the climbable integral block formation;

FIG. 4 is a bottom view of the climbable integral block formation;

FIG. 5 is a front view of the climbable integral block formation;

FIG. 6 is a rear view of the climbable integral block formation;

FIG. 7 is a right side view of the climbable integral block formation; and,

(Continued)

FIG. 8 is a left side view of the climbable integral block formation.

The broken lines in the drawings illustrate features that form no part of the claim.

1 Claim, 6 Drawing Sheets
